DROP-IN GRILL FOR A RADIATOR ENCLOSURE OR THE LIKE

Robert H. Sand, Canton, Conn., assignor to The Vulcan
Radiator Company, Hartford, Conn., a corporation of
Connecticut

Filed Nov. 1, 1966, Ser. No. 4,505

Term of patent 14 years

(Cl. D23—115)

Fig. 1

Fig. 2

Fig. 3

Fig. 4

Fig. 5

FIG. 1 is a perspective view of a drop-in grill for a radiator enclosure or the like embodying my new design.

FIG. 2 is a perspective view thereof shown in an inverted position.

FIG. 3 is a side elevational view thereof.

FIG. 4 is a sectional view thereof taken along line 4-4 of FIG. 1.

FIG. 5 is a view similar to that of FIG. 4 but showing an alternate form of vane configuration.

FIGS. 1, 2, and 3 have been broken away to indicate indeterminate length.

I claim:

The ornamental design for a drop-in grill for a radiator enclosure or the like, as shown and described.
